F. P. WILLIAMS.
SHEET METAL DRAWER.
APPLICATION FILED MAY 2, 1921.

Patented Jan. 24, 1922.

FRANK P. WILLIAMS
BY *Stuart E. Barnes*,
ATTORNEY.

UNITED STATES PATENT OFFICE.

FRANK P. WILLIAMS, OF DETROIT, MICHIGAN.

SHEET-METAL DRAWER.

1,404,503.

Specification of Letters Patent. Patented Jan. 24, 1922.

Application filed May 2, 1921. Serial No. 466,005.

To all whom it may concern:

Be it known that I, FRANK P. WILLIAMS, a citizen of the United States, residing at Detroit, in the county of Wayne 5 and State of Michigan, have invented certain new and useful Improvements in Sheet-Metal Drawers, of which the following is a specification.

This invention relates to drawers, and has 10 for its object a drawer construction that is suitable for a sheet metal cabinet, desk or other article of furniture.

In the drawings,—

Fig. 1 is a perspective of an assembled 15 drawer.

Fig. 2 is a cross section of the same.

Fig. 3 is a fragmentary section on the line 3—3 of Fig. 2.

Fig. 4 is a section on the line 4—4 of 20 Fig. 3.

The drawer comprises a front plate *a* having turned-over side edges *b* and a twice doubled back bottom edge *d*. The side 25 plates and rear plate are made from a single strip of sheet metal folded to provide the side plates *e* and *f* and the rear plate *g*. Each of these plates has a strip of metal folded outwardly perpendicularly and re-turned upon itself to form the reinforcing. 30 flanges *e'*, *f'* and *g'*. The rear plate *g* is provided at the bottom with a rearwardly and perpendicularly formed flange *j*. The side plates *e* and *f* are provided with outwardly-extending side flanges *f²* and *e²*. 35 This enables the flanges *f²* and *e²* to be slid into the turned-back side edge portions *b* of the front plate *a*, thereby completing the side enclosure of the drawer.

The bottom *h* may be locked in by slipping 40 the turned-back hook *l* at the rear of the bottom over the rearwardly-projecting flange *j* of the rear plate *g* and then forcing the downwardly-directed flange *m* at the front of the bottom into the twice 45 doubled-back lock-seam fold *d* at the bottom of the front plate. The bottom plate is provided with side flanges *k'* which slip into upwardly-turned folds *w* in the side walls, as is best shown in Fig. 4.

50 A shallow reinforcing channel sheet *o* may be slipped in behind the front plate *a* and between the side walls *f* and *e*. This acts as a side wall spacer and holds the flanges *f²* and *e²* in place and also holds the flange 55 *m* of the bottom plate *h* in place. This channel sheet is formed with an upwardly-

extending flange *p* that locks into the upper turned-over edge of the front plate *a* and the ends of the channel are closed by the perpendicular folds *q*. When the knobs *r* 60 are bolted in place by the nuts and bolts *s* this secures the channel reinforcing sheet to the front plate and completes the assembly of the drawer parts and locks the sides and bottom in such relation to each 65 other and to the front plate that they cannot come apart without disassembling the knobs and taking out the channel sheet.

What I claim is:

1. In a sheet metal drawer, a front plate 70 provided at its bottom with a turned-up fold, side and rear plates, the latter provided with a rearwardly turned-out flange, and a bottom plate having its rear edge turned over into a hook adapted to hook 75 over the turned-back flange of the rear plate and having a turned-down flange at the front adapted to be forced into the turned-up fold of the front plate.

2. In a sheet metal drawer, a front plate 80 provided at its bottom with a turned-up fold, side and rear plates connecting the front plate, said rear plate being provided with a rearwardly-extending flange, a bottom plate provided at its rear with a turned- 85 over edge forming a hook engaging said turned-back flange of the rear plate and having at its forward end a turned-down flange adapted to be forced into the turned-up fold of the front plate, and a reinforcing member engaging behind the front plate 90 and bearing on the front of the bottom plate to hold the flange of the same locked into the fold of the front plate.

3. In a sheet metal drawer, the combination 95 of a front plate having turned-over side edges and a folded-up bottom edge, side walls formed by a single strip of metal folded to form rear and side plates, the former provided with a turned-back flange at the 100 bottom and the latter provided with turned-out flanges at the front engaging in the turned-over side edges of the front plate, and a bottom plate having a hook-like rear edge portion engaging over the turned-back 105 flange at the bottom of the rear plate and having a turned-down flange at the front engaging in the folded-up bottom edge of the front plate.

4. In a sheet metal drawer, the combination 110 of a front plate provided with side edges with turned-over portions and at its

bottom with a turned-up fold, side walls formed of a single strip of metal forming the rear and the side plates, the former provided at its bottom with a turned-back flange 5 and the latter provided at the front with turned-out flanges adapted to engage under the side edges of the front plate, and a bottom plate provided at its rear with a hook-like edge adapted to lock over the turned-back flange of the rear plate and having at the front a turned-down flange engaging in the turned-up fold of the front plate, and a reinforcing member secured to the front plate in back thereof and spacing the side plates and serving to lock the side plate flanges into the turned-over side edges of the front plate and serving to lock the turned-down front edge of the bottom plate in the turned-up fold of the front plate.

20 5. In a sheet metal drawer, the combination of a front plate having at its bottom a turned-up fold, a single sheet of metal formed into a rear plate and two side plates connected with the front plate, said side plates 25 having at their bottom turned-up edges and the rear plate having a rearwardly-extending flange at the bottom, and a bottom plate provided at its rear with a turned-over hook portion adapted to engage over the turned-back portion of the rear plate and having at the sides turned-down flanges adapted to en-

gage with the turned-up side edges and having at its front a turned-down flange engaging in the turned-up fold of the front plate.

6. In a sheet metal drawer, the combination of a front plate provided at its bottom with a turned-up fold, side plates locking into the front plate and provided with turned-up folds, a rear plate connected with the side plates, and a bottom plate locking into the rear plate and provided with turned-down flanges at the front and sides locking into the turned-up folds of the front plates and side plates.

7. In a sheet metal drawer, the combination of a front plate provided with turned-over side edges and a turned-up bottom edge, side plates with turned-out flanges engaged by the turned-over side edges of the front plate and also provided with turned-up bottom edges, a rear plate connecting with the side plates, a bottom plate locking into the rear plate and provided with turned-down flanges at the front and sides, said flanges locking into the turned-up edges of the front and side plates, and a reinforcing member fitting in behind the front plate and in between the side plates and above the bottom plate and serving to keep the side plates and the bottom plate locked in place.

In testimony whereof I affix my signature.
FRANK P. WILLIAMS.
